WATER HEATER

John J. MacNeill, New York, N. Y.

Application June 6, 1938, Serial No. 212,196

1 Claim. (Cl. 126—54)

This invention relates to water heaters for use in conjunction with heating elements of gas, electric and oil stoves or ranges.

- The principal object of the invention is the provision of a water heater embodying improvements in construction whereby the thermal efficiency thereof is increased and whereby the installation of one or more heaters may be readily achieved.
- 10 A further object of the invention is the provision of a heater of the indicated character whereby water may be heated while cooking, baking and roasting in the usual manner in order to economize the use of gas, electricity and oil, as the case may be.

15 The nature of the invention and the distinguishing features and advantages thereof will appear when the following specification is read in connection with the accompanying drawing, in which:

Fig. 1 is a plan view, partly in section, of a combined water heater and gas burner constructed in accordance with the invention.

20 Fig. 2 is a view of a portion of the water heater looking toward the underside thereof.

Fig. 3 is a side view, partly in section, of the combined water heater and burner.

25 Referring now more particularly to Figs. 1, 2, and 3, it will be apparent that there is shown a water heater 8 and a heating element 9, the same being in the form of a gas burner in the present instance. It is to be understood that any other form of heating element may be used, such as an electric element or an oil burner. The water heater 8 consists of a hollow body 10 substantially square in the present instance. The body 10 consists of an outer wall 11, an inner wall 12, top wall 13 and a bottom wall 14. The outer wall 11 is substantially square with rounded corners, and 30 the inner wall 12 is circular or annular. The top wall 13 is convex and the bottom wall 14 is straight. The various walls define a water space 15 consisting of relatively wide areas 16 at the corners of the body 10 joined by narrow areas 17.

35 The inner wall 12 defines the heat passage 18 located centrally of the body 10. The wall 12 has a plurality of grooves 19 therein to increase the heating surface of the wall 12. A lip 20 is formed integral with the body 10 at the juncture between

the inner wall 12 and the top wall 13. This lip 20 projects inwardly with respect to the heat passage 18 and constitutes a baffle to retard the up-flow of heated air. The sides of the outer wall 11 are tapped to provide a cold water inlet 21 and a plurality of hot water outlets 22. Thus, provision is made for using a single water heater or for making a multiple connection of a plurality of heaters. Suitable plugs 23 are provided to close the tapped openings not used. The underside of the wall 14 has bosses 24 for the purpose of connecting the water heater with the heating element or gas burner 9, the latter being provided with lugs 25 for that purpose. The heating element 9 is of conventional construction and includes circular series of gas orifices 26 which distribute or direct the flames upwardly in proximity to the bottom and inner walls of the water heater 8. The burner has the usual feed pipe 27 to supply a mixture of gas and air to the burner.

In use, a vessel containing the food substances and liquids to be cooked or boiled is placed on the water heater 8. At the same time water admitted to the water space of the heater 8 will be heated thereby economizing on the use of gas. By providing a water space consisting of relatively wide and narrow areas 16 and 17, respectively, the water will be caused to eddy at the corners, or in other words, as the water flows in the water space 15 it will be given a rotary motion, thereby causing a more rapid heating of the water. As stated above, by providing the grooves 19 the heating surface of the inner wall 12 of the body is increased, thereby increasing the heating efficiency.

What I claim as new is:

A device of the character described comprising, a hollow substantially square-shaped body adapted to be supported above a heating element and providing a water space and heat passage, said water space comprising relatively wide areas at the corners of the body joined by relatively narrow areas, the wall of the body surrounding said passage being grooved to increase the heating surface thereof, and a baffle projecting inwardly from said body with respect to said passage to retard the flow of heated air.

JOHN J. MACNEILL.
